UNITED STATES PATENT OFFICE.

HARRY P. THOMAS, OF AKRON, NEW YORK, ASSIGNOR OF ONE-HALF TO
MERRILL H. BUELL, OF AKRON, NEW YORK.

CLEVIS.

SPECIFICATION forming part of Letters Patent No. 781,696, dated February 7, 1905.

Application filed September 24, 1904. Serial No. 225,812.

To all whom it may concern.

Be it known that I, HARRY P. THOMAS, a citizen of the United States, residing at Akron, in the county of Erie and State of New York, have 5 invented a new and useful Clevis, of which the following is a specification.

This invention relates to the clevises of plows, cultivators, and similar implements, and has for its object to produce a simply-constructed and easily-applied device of this character whereby the doubletree, swingletree, or draft-beam members are prevented from sagging or dropping to the ground when the draft strains are removed, while at the same 15 time retaining all the necessary flexibility of movement and ability to adjust the same as required.

With these and other objects in view, which will appear as the nature of the invention is 20 better understood, the same consists in certain novel features of construction, as hereinafter fully described and claimed.

In the accompanying drawings, forming a part of this specification, and in which corresponding parts are denoted by like designating characters, is illustrated the preferred form 25 of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

35 In the drawings thus employed, Figure 1 is a side elevation of the improved device applied. Fig. 2 is a plan view of the same. Fig. 3 is a perspective view of certain members of the improved device disconnected, and Fig. 40 4 is a side elevation of a modified form of clevis.

The improved device may be applied with slight and unimportant modifications to any 45 of the various forms of draft appliance employed upon plows, cultivators, and similar implements, and for the purpose of illustration the device is shown in Figs. 1 and 2 as applied to an ordinary steel-beam clevis and in Fig. 4 to an ordinary wood-beam clevis.

The improved device comprises a stock 10, 50 having spaced ears 11 12 and a depending shoulder 13 and a head member 14, pivoted, as at 15, between the ears 11, said head member being provided with a depending shoulder 16, adapted to bear against the shoulder 13 of 55 the member 10. By this means the member 14 is limited in movement in one direction relative to the member 10, but free to swing in the opposite direction, as will be obvious. The rear end of the member 10 is provided 60 with an oblong stud 17, adapted to enter a similarly-shaped aperture in the hub 18 of a clip 19, the latter being attached, as by a pin or bolt 20, to the horizontal member 21 of the plow-clevis. The forward end of the member 14 is provided with a stud 22, upon which a clip 23 is swiveled, said clip serving to support the doubletree or draft-beam, a portion of which is represented at 24, as by a pivot-pin 25. The studs 17 and 22 are screw-threaded at their free ends to receive binding-nuts 26 27, respectively. The clevis member 21 is formed with spaced arms 28 29, extending rearwardly and pivoted, as by bolt 30, to the plow-beam 31 and likewise to the spaced clevis 75 members 32 33, the clevis member 21 being adjustably connected to the clevis members 32 33 by the pin 34 in the ordinary manner. By this arrangement it will be obvious that the clip 19, while free to swing laterally upon the member 21, cannot move vertically, and the member 10, being rigidly connected to member 21 by the oblong or square stud 17 and nut 26, is likewise held from vertical 80 movement, but free to swing laterally with 85 the clip 19. It will also be obvious that the evener-beam 24, while free to swing horizontally upon its pivot 25 and to rotate vertically upon the pivot 22 and also to swing upward upon the pivot 15, cannot move downward be- 90 yond a certain degree, because of the limitations caused by the coacting shoulders 13 16. By this means the evener-beam, while free to move in all necessary directions, cannot drop down upon the heels of the draft-animals 95 when the draft strains are removed from any cause. Thus when stopping the plow or when backing or turning the eveners will be main-

tained in position and prevented from falling and annoying the horses or driver.

When applied to a wood plow-beam 35, as in Fig. 4, a clevis of slightly-modified form 5 will be employed, said clevis consisting of a pair of spaced arms 36 37, secured, as by pins or bolts 38 39, to the beam 35 and provided with a horizontal lug 40, adapted to engage the clip 19, as by the pin 20, it being necessary, as before stated, to hold the clip 19 from vertical movement, while leaving it free to swing horizontally.

While I have shown two forms of plow-clevises to illustrate the application of the invention, it will be understood that I do not wish to be limited in any manner thereby, as the clevis or other coupling means between the clip 19 and the plow-beam is not a part of my invention, and the improved device may 20 be coupled to the plow-beam by any suitable means which will permit it to operate as above described.

Having thus described the invention, what is claimed is—

25 1. In a clevis for plows and the like, a stock having means for attachment to the draft-beam for swinging horizontally thereon and provided with spaced vertical ears and a depending stop-shoulder, and a carrier member 30 having means for attachment to the evener-

beam for rotation thereon and pivoted to swing between said spaced ears and provided with a depending shoulder adapted to bear against the stop-shoulder of said stock member.

35 2. In a clevis for plows and the like, a stock member having at one end spaced vertical ears and a depending shoulder and at the opposite end thereof a rectangular stud provided with a threaded extension, a clip 40 provided with spaced arms for horizontal swinging connection to the draft-beam and having an apertured hub adapted to engage said rectangular stud and held thereon by a nut engaging the threaded extension, a carrier member having at one end a threaded stud and pivoted at the other end between the ears of said stock and provided with a depending lug adapted to bear against the lug on said stock, and a clip mounted for rotation upon said 45 threaded stud and held thereon by a nut and provided with spaced arms for embracing the evener-beam and pivoted thereto.

50 In testimony that I claim the foregoing as my own I have hereto affixed my signature in 55 the presence of two witnesses.

HARRY P. THOMAS.
